DESIGN FOR A STREET LAMP

Hilyard R. Robinson, Washington, D. C., and
Aksel J. C. Knudstrup, Vienna, Va.

Application November 10, 1938, Serial No. 81,022

Term of patent 14 years

To all whom it may concern:

Be it known that we, Hilyard R. Robinson and Aksel J. C. Knudstrup, citizens of the United States, residing at Washington, District of Columbia, and Vienna, county of Fairfax, and State of Virginia, have invented a new, original, and ornamental Design for a Street Lamp, of which the following is a specification, reference being had to the accompanying drawing, forming a part thereof.

In the drawing:

Figure 1 is a side elevational view of a street lamp showing our new design, and

Figure 2 is a vertical sectional view through the upper portion of the lamp.

The dominant features of our new design are shown in full lines in the drawing.

We claim:

The ornamental design for a street lamp, as shown and described.

HILYARD R. ROBINSON.
AKSEL J. C. KNUDSTRUP.
